US0D1046831S

(12) **United States Design Patent** (10) **Patent No.:** **US D1,046,831 S**
(45) **Date of Patent:** **** Oct. 15, 2024**

(54) **GROUND-BASED COMMUNICATION MODULE**

(71) Applicant: **Calective LLC**, Escondido, CA (US)

(72) Inventors: **Lydell Aaron**, Laguna Niguel, CA (US); **Benjamin De Villa**, Murrieta, CA (US)

(73) Assignee: **Calective LLC**, Escondido, CA (US)

(**) Term: **15 Years**

(21) Appl. No.: **29/864,031**

(22) Filed: **May 5, 2022**

Related U.S. Application Data

(63) Continuation of application No. 17/732,306, filed on Apr. 28, 2022, now Pat. No. 11,622,274.

(57) **CLAIM**

The ornamental design for a ground-based communication module, as shown and described.

DESCRIPTION

FIG. 1 is a perspective view of a ground-based communication module to the new design.

FIG. 2 is a front view of the module of FIG. 1.

FIG. 3 is a rear view of the module of FIG. 1.

FIG. 4 is a left side view of the module of FIG. 1.

FIG. 5 is a right side view of the module of FIG. 1.

FIG. 6 is a top plan view of the module of FIG. 1; and, FIG. 7 is a bottom plan view of the module of FIG. 1.

The broken lines shown in the figures illustrate portions of the article, and form no part of the claimed design.

1 Claim, 7 Drawing Sheets
